ATTORNEY

UNITED STATES PATENT OFFICE

DORA ELIZABETH CAMPBELL, OF PATERSON, NEW JERSEY

WINDOW-CLEANING APPARATUS

Application filed September 27, 1926, Serial No. 137,955. Renewed March 29, 1929.

This invention relates to window cleaning apparatus and more particularly to window cleaning apparatus with which the operator works within the room.

5 The principal object of the invention is to provide an improved apparatus of this class in which the parts are few and simple, and with which windows can be safely cleaned from within the room with storm sash or full 10 length outside screen in place if described. Another object is to provide a window cleaning apparatus of this class which can be economically manufactured and which will take up but little space when stored away. A further 15 object is to provide a member that is adapted to hold inexpensive and readily applied cleaning and drying elements so that they can be moved between two window sashes close together. Still another object 20 is to provide means to move said holding member in such position. Another object is to provide improved means for use on the edge portions of window sashes for assisting in the manipulation of the holding member 25 and cleaning element. And a further object is to provide a neat, compact and efficient apparatus of the class described.

The means I prefer to employ for accomplishing the above-named objects, together 30 with other advantageous features of my improved window cleaning apparatus not hereinbefore mentioned but which will appear as the description progresses, are illustrated in the drawings accompanying and forming 35 part of this specification, and in which—

Figure 1 is a vertical section of a window showing my improved cleaning apparatus in an operating position.

40 Fig. 2 is an elevation of the same taken from within the room.

Fig. 3 is a vertical section of a window with my cleaning apparatus in another operating position.

45 Fig. 4 is a rear elevation of the member for holding the cleaning element of my apparatus, together with the operating band and omitting the cleaning element.

Fig. 5 is a front elevation of the same omitting the operating band.

Fig. 6 is a longitudinal section taken on the line 6—6 of Fig. 5.

Fig. 7 is a plan of a cleaning element for use with my apparatus.

Fig. 8 is an end elevation of the same.

Fig. 9 is a perspective view of one of the carrier members for use with my apparatus.

Fig. 10 is a perspective view of another form of carrier member, and

Fig. 11 is a transverse section of the above 60 two forms of carrier member united for joint use.

Like characters of reference refer to like parts in all the figures of the drawings.

Referring to the drawings and particularly to Figs. 1 to 6 inclusive, the numeral 2 indicates a member adapted to be moved up and down for window cleaning purposes between two slidable window sashes such as the lower or inner sash 3 and the upper or outer sash 4 of Fig. 3 or between a slidable sash 4 and a fixed outer sash or member such as the storm sash 5 of Fig. 1 or a full length screen which would occupy substantially the same position.

The movable member 2 may be of any suitable form but the form which I prefer to employ embodies an outer portion such as 7 and one or more inner portions such as 8, joined to said outer portion 7 in any suitable way as by end portions such as 9. A space such as 2' is preferably formed between the two portions 7 and 8, the purpose of which will more fully appear hereinafter. Preferably the portions 7, 8 and 9 are of sheet metal of suitable thickness and integral, being preferably formed from a single sheet of said metal.

As hereinbefore-mentioned, the said member 2 is adapted for movement up and down, and such movement may be effected in any suitable manner but preferably I employ a member such as the elongated flexible member or band 11. The said flexible member 11 may be connected to the member 2 in any suitable way but preferably I provide perforations or slots such as 12 in the outer portion 7 of said member 2, and the member 11 is passed through said perforations as illustrated in Figs. 1, 2, 3 and 4.

It is necessary to attach the said member 11 100

firmly to the member 2 and any suitable means may be employed for this purpose. Preferably I effect this by providing serrations or teeth such as 13 on one or more of the edges of the perforations or holding slots 12, which teeth are caused to enter slightly into the material of the member 11 and are thus effective for holding said member firmly secured to the portion 7. The member 11 is formed of any suitable material and may be of any suitable length, and in practice I ordinarily form it of fabric of suitable firmness and about eight feet in length but the length can be varied to suit conditions. Ordinarily it extends from the member 2 in two portions of substantially equal length. Preferably I provide attachments such as 16, which is a wire loop, and 17, which is a member to engage with the member 16, said members being firmly secured to the end portions of the member 11, serve as means to connect them together when desired. Each of the end portions of the member 11 is provided with a small weight such as 18 secured to it in any suitable manner as by doubling the material and sewing the edges around the weight. The purpose of said weights is in assisting in placing the member 11 in position between the outer and inner window sashes together with the member 2, one of the weighted end portions being first lowered between said sashes. Also in placing the members 11 and 2 between the sash 4 and storm sash 5 as illustrated in Fig. 1.

Any suitable form of cleaning element may be used with my improved apparatus, but preferably I employ cleaning elements formed of muslin cloth in several thicknesses as indicated in Figs. 7 and 8 where 19 denotes the cleaning element and 19' indicates a narrow space into which the portions 8 of the member 2 can be pushed for placing it on said member.

For assisting in and guiding the movements of the member 11, I have provided members which I term carrier members, and in Fig. 9 I have illustrated one form of such carrier member which is indicated by 21 and is adapted to be placed on the bar 22 of the sash 3. The said member 21 is preferably formed with a rounded portion such as 23 over which the member 11 can freely slide. I also provide guiding portions such as the side flanges 24 so that the member 11 will not slip off the portion 23 when being moved to and fro over the same. Any suitable means may be provided to hold the said member 21 on the window sash but preferably I employ one or more depending portions such as the portions 25, of which in the form illustrated in Fig. 9 there are two, one for each side of the bar of the window sash. In the form illustrated there is a slot such as 26 substantially horizontal when in use and is formed between the

portion 23 and a metal plate such as 27 for a purpose which will presently be described.

In Fig. 10, I have illustrated another form of carrier member which is indicated by 29, and has a rounded portion 23, side flanges 24 and one depending portion 25 to engage a bar of a window sash. On the opposite side to the depending portion 25 opposite the upper part thereof is a substantially horizontal portion such as 30 which projects outwardly from the base of the rounded portion 23 and which portion I ordinarily term the projecting portion. It is adapted to be inserted in the slot 26 of the carrier member 21 so that the two members can be joined together as illustrated in Figs. 1 and 11. This arrangement provides for guiding the member 11 when cleaning the outside of an upper window sash as illustrated in Fig. 1.

In practice I provide the members 21 in several sizes so as to fit windows of different thicknesses of top bars and thus provide an outfit whereby all sizes of windows in ordinary use can be readily cleaned with my invention.

The operation of cleaning a window with my improved apparatus is as follows:

For cleaning the upper sash 4 of a window, the carrier member 29 is first connected to the carrier member 21 by placing its projecting portion 30 in the slot 26 as illustrated in Fig. 11, and the two members thus connected are then placed so that they rest respectively on the upper edge portions of the sashes 4 and 3, which must be brought into substantial alinement with each other by lowering the upper sash and raising the lower sash.

The flexible member 11 must now be attached to the member 2 and the cleaning cloth or element 19 must be in place thereon, a portion of it being in the space 2' provided therefor and illustrated in Figs. 1 and 3. One of the end portions of the member 11 is now let down between the upper sash 4 and the storm sash 5 or screen if the latter is in place, being assisted by the weight 18 in said end portion, and with it is lowered the member 2 and cleaning element or cloth 19 thereon until the inner face of the cloth 19 is adjacent the pane 34 of the upper sash. The upper portion of the member 11 is now placed over the rounded portions 23, 23, of the two carrier members 21 and 29 and between the flanges 24. The upper and lower portions of the member 11 are now pulled alternately by the hands, and the member 2 and cleaning cloth 19 are moved up and down across the pane with 19 in contact therewith until the glass is sufficiently cleaned. Drying of the pane may be effected by another member 2, cloth 19, and member 11 attached. The carrier members are moved laterally along the bars of the respective sashes to bring the members 2 and 11 to operate at all parts of the pane, the members 21 and 29

constituting laterally shiftable means to guide said members in this case, and in the following instance merely the member 21 constitutes said means.

The lower sash is cleaned in a manner similar to that just described except that the member 29 is removed from the member 21 and from the sash 4. The latter sash is then lowered a few inches as shown in Fig. 3, and the lower portion of the member 11 is lowered between the sashes 3 and 4 with the member 2 and cloth 19 following until the latter is in contact with the pane 36 of the sash 3. The upper part of the member 11 is carried around the carrier member 21 with the latter on the upper bar 22 of the sash 3. The members 2 and 11 are now manipulated as in the cleaning of the sash 4.

In some instances the carrier members 21 and 29 may be formed in two or more parts, one of which may include the rounded portions 23 which may be of wood or other suitable material, and another part may be of sheet metal and include the portions 24, 25 and 27 or 30 according to the type of carrier. The part having the rounded portions 23 may be secured to the flanges 24 by suitable means such as small nails 38.

From the foregoing it will be apparent that with my apparatus the outsides of the panes of substantially all types of sliding windows including both very high and very low windows, can be completely cleaned and dried with entire safety to the operator. Also the operator does not work in a cramped position at any time during the cleaning and drying operations.

It is evident that the different parts of the apparatus may be modified or changed in various ways and any suitable forms of parts may be employed without departing from the principle of the invention, and I do not therefore confine myself to the details of construction here shown.

What I claim is:—

1. A window cleaning apparatus embodying a member of sheet metal having its ends folded upon itself to provide flaps spaced from the body to support a wiper pad, said member being adapted to be moved in the space between the outer and inner sashes of a window, a flexible member of suitable length adapted to be secured to the first-mentioned member for moving the same, and means adapted to be held by the window for guiding the flexible member.

2. A window cleaning apparatus embodying a member adapted to support a cleaning element, having a portion provided with spaced toothed perforations, and adapted to be moved between the outer and inner sashes of a window, a flexible member passing through said perforations, and means adapted to be held on the edge portion of a window sash for guiding said flexible member and

over which the same can be pulled for moving the first-mentioned member.

3. A window cleaning apparatus embodying a member provided with an outer portion having spaced toothed perforations, an inner portion adapted to support a cleaning element, and a space between said portions in which a part of said cleaning element can lie, said member being adapted to be moved in the space between the outer and inner sashes of a window, a flexible member of suitable length passing through said perforations and means adapted to be secured on and movable laterally along an edge portion of a window sash for guiding said flexible member and over which it can be pulled for moving said first-mentioned member.

4. A window cleaning apparatus embodying a sheet metal member provided with a single ply outer portion having spaced toothed holding slots, and two single ply inner portions on which a cleaning element can be held and having a space between them for assisting in the placing of the cleaning element, a cleaning element adapted to be held by said portions, a carrier member adapted to be held on an edge portion of a window sash, and a flexible band passing through said slots and adapted to be pulled around and guided by the carrier member when moving the first-mentioned member up and down on pulling the end portions alternately.

5. The combination with a window cleaning apparatus embodying a member movable up and down along a window sash and adapted for carrying a cleaning element, and a flexible member for moving the first-mentioned member, of a member adapted for attachment to a window sash and movable laterally along the same, which member includes a rounded portion over which the flexible member can be pulled, two flanges one on each side of the rounded portion to limit the lateral movement of the flexible member, and a lower depending portion to engage the window sash which portion is at right angles to said flanges.

6. The combination with a window cleaning apparatus embodying a member movable up and down along a window sash and adapted for carrying a cleaning element, and a flexible member for moving the same, of a carrier member provided with a rounded portion and a substantially horizontal slot under the same, and a second carrier member having a rounded portion and an adjacent projecting portion adapted to be inserted in said slot of the first-mentioned carrier member, said carrier members being adapted to be held respectively on the upper edge portions of the upper and lower sashes of a window, and over the rounded portions of said carrier members the flexible member can be pulled for moving the first-mentioned member.

7. The combination with a window cleaning apparatus embodying a member movable up and down and adapted for holding a cleaning element, and a flexible member for moving the same, of a two part member, the said parts being attached respectively to the edge portions of two sashes of a window, one of said parts having an extension for spanning the sashes and resting upon and securing said part to the other part of said two part member and said member having a portion over which the flexible member can be pulled and portions to limit the lateral movement of the same. 70
- 10 8. A window cleaning apparatus embodying a member having an outer wall and inner upright walls with a space between them extending therethrough from top to bottom, said inner walls being adapted to support a cleaning element and having a space between them for the insertion of the same, a flexible member adapted to be secured to the first-mentioned member for moving the same, and means adapted to be held on the edge portion of a window sash for guiding the flexible member. 80
- 15 9. A window cleaning apparatus embodying an operating band, a cleaning pad holder provided with sheet metal front and rear upright walls spaced apart from each other a distance less than that between the glass of the lower sash and the frame of the upper sash and a fixed element at each side connecting said front and rear walls, said holder being adapted for holding a cleaning element, the rear of said walls embodying means for securing said band to said holder, and means adapted to be placed on the top edge of a sash for guiding said band. 85
- 20 10. A window cleaning apparatus embodying an operating band, a cleaning pad holder having sheet metal front and rear walls, sheet metal end portion for connecting said front and rear walls and means to secure said band to said holder, there being a space between and surrounded by said walls and end portions and extending through said holder, said holder being adapted for carrying a cleaning element, and also being adapted to pass between the upper and lower sashes of a window when said sashes are opposite, and means to be placed on the top of a sash for guiding said band. 90
- 25 11. The combination with a window cleaning apparatus embodying a member movable up and down and adapted for holding a cleaning element, and a flexible member for moving the same, of a two part member, said parts being attached respectively to the two sashes of a window, said member having means whereby said parts are movably joined to each other, a portion over which the flexible member can be pulled, and portions to limit the lateral movement of the same. 95
- 30 12. A cleaning pad holder for a window 100
- 35 13. A window cleaning apparatus embodying an operating band, a cleaning pad holder having sheet metal front and rear walls, sheet metal end portion for connecting said front and rear walls and means to secure said band to said holder, there being a space between and surrounded by said walls and end portions and extending through said holder, said holder being adapted for carrying a cleaning element, and also being adapted to pass between the upper and lower sashes of a window when said sashes are opposite, and means to be placed on the top of a sash for guiding said band. 105
- 40 14. A window cleaning apparatus embodying an operating band, a cleaning pad holder having sheet metal front and rear walls, sheet metal end portion for connecting said front and rear walls and means to secure said band to said holder, there being a space between and surrounded by said walls and end portions and extending through said holder, said holder being adapted for carrying a cleaning element, and also being adapted to pass between the upper and lower sashes of a window when said sashes are opposite, and means to be placed on the top of a sash for guiding said band. 110
- 45 15. A window cleaning apparatus embodying an operating band, a cleaning pad holder having sheet metal front and rear walls, sheet metal end portion for connecting said front and rear walls and means to secure said band to said holder, there being a space between and surrounded by said walls and end portions and extending through said holder, said holder being adapted for carrying a cleaning element, and also being adapted to pass between the upper and lower sashes of a window when said sashes are opposite, and means to be placed on the top of a sash for guiding said band. 115
- 50 16. A window cleaning apparatus embodying an operating band, a cleaning pad holder having sheet metal front and rear walls, sheet metal end portion for connecting said front and rear walls and means to secure said band to said holder, there being a space between and surrounded by said walls and end portions and extending through said holder, said holder being adapted for carrying a cleaning element, and also being adapted to pass between the upper and lower sashes of a window when said sashes are opposite, and means to be placed on the top of a sash for guiding said band. 120
- 55 17. A window cleaning apparatus embodying an operating band, a cleaning pad holder having sheet metal front and rear walls, sheet metal end portion for connecting said front and rear walls and means to secure said band to said holder, there being a space between and surrounded by said walls and end portions and extending through said holder, said holder being adapted for carrying a cleaning element, and also being adapted to pass between the upper and lower sashes of a window when said sashes are opposite, and means to be placed on the top of a sash for guiding said band. 125
- 60 18. A window cleaning apparatus embodying an operating band, a cleaning pad holder having sheet metal front and rear walls, sheet metal end portion for connecting said front and rear walls and means to secure said band to said holder, there being a space between and surrounded by said walls and end portions and extending through said holder, said holder being adapted for carrying a cleaning element, and also being adapted to pass between the upper and lower sashes of a window when said sashes are opposite, and means to be placed on the top of a sash for guiding said band. 130
